CELLULOSE CORD

Morris Katz, Bronx, N. Y.

Application December 21, 1935, Serial No. 55,525

12 Claims. (Cl. 117—53.5)

This invention relates to cords, strands or similar material which may be used for tying packages as well as a strand for weaving, braiding or otherwise forming articles of manufacture; and the 5 object of the invention is to provide a strand of the class described having a core in the form of a string of cotton or similar material or which may be composed of other fibrous material, preferably capable of being readily saturated, and further- 10 more of holding a saturant, and to arrange on the core one or more strips of cellulose material, such for example as "cellophane" which is in the form of a relatively thin strip or ribbon which may be laid along the core and folded and twisted 15 or which may be spirally wound thereon; a further object being to provide narrower strips of other ornamental material, preferably of a color contrasting to the color of the cellulose strip to enhance the appearance of the resulting product 20 and further to aid in supporting the cellulose covering thereon; a further object being to provide a cord or strand of the class described composed of two or more cellulose coverings of contrasting colors, in conjunction with which may be 25 employed narrower strands of contrasting material; a still further object being to provide a cord having a core or inner body consisting of a cord around which is arranged a covering of paper, tissue or other material upon which the cellulose strip or strips are applied; and with 30 these and other objects in view, the invention consists in an article of manufacture of the class described which is produced in accordance with the method more fully hereinafter described and 35 claimed.

The invention is fully disclosed in the following specification, of which the accompanying drawing forms a part, in which the separate parts of my improvement are designated by suitable 40 reference characters in each of the views, and in which:

Fig. 1 is a diagrammatic view illustrating the steps and the method of producing one form of strand according to my invention.

45 Fig. 2 is a partial section on the line 2—2 of Fig. 1 on an enlarged scale.

Fig. 3 is a partial section on the line 3—3 of Fig. 1 on an enlarged scale.

Fig. 4 is an enlarged side view of a strand produced from the method diagrammatically illustrated in Fig. 1.

Fig. 5 is a view similar to Fig. 4 showing another form of strand which I may employ; and,

Fig. 6 is a cross sectional view of a strand showing another modification.

In Fig. 1 of the drawing, I have shown for the purpose of illustrating one means of carrying my improved method into effect a diagrammatic illustration of the several steps of one method which I employ. In said figure, at 10 I have shown a 5 supply spool 10 of cotton cord 11 which is adapted to pass into and through a vat or tank 12 containing a suitable saturant 13, such for example, as glycerine, or in some cases, a combination of glycerine and water. It will be understood that 10 other saturants may be employed.

Before passing into the tank 12, the cord 11 passes through a tension device 14 which serves to keep the cord taut at all times as it is fed through the apparatus. After being submerged in the 15 saturant 13, the saturated cord passes through a suitable wiper 15 for removing excess saturant. This wiper may be controlled so as to regulate the amount of saturant maintained in the cord 11. At 16, I have shown a supply spool of a strip 17 of 20 cellulose material, such for example as "cellophane". The strip 17 may be of any desired color and mounted upon a white or light colored cord 11, or if desired, the cord may be of a color substantially similar to that of the color of the 25 strip 17.

As the strip 17 passes onto the cord 11, the same is folded by a suitable tool 18 into a substantially channel form as indicated at 17a in Fig. 2 of the drawing. As the cord 11 with the strip 17 thereon 30 passes through the apparatus, one or more narrow strips or strands 19, 19a, two of such strands being shown in the accompanying drawing, are spirally wrapped around the U or channel strip 17a, the result of which will curl or fold the strip around 35 the strand 11 in the manner indicated at 17b in Fig. 3 of the drawing so as to completely envelop the core 11 and to form a substantially round resulting strand.

I next pass the strand thus formed around a 40 number of rollers 20 which are preferably mounted in a revolving frame so as to apply a slight twist in the resulting strand to more firmly retain and secure the strip 17 to the core string 11, it being understood that the saturant will have 45 had time to loosen or soften the strip 17; and as the strip 17 dries externally to some degree, the same will become set upon the core cord 11, which is mounted upon a receiving spool 21, preferably shiftable upon a shaft 22 to facilitate winding 50 with respect to the fixed guide roller 23. A shifting arm is represented at 24 in Fig. 1 of the drawing. The spool 21 may revolve with the frame or an independent take-off which will not interfere with the twisting operation. The finished 55

strand which is also herein referred to as a cord may be wound upon a large spool or drum and then rewound or wrapped for retail or other sale, or if desired, may be directly wound upon 5 spools for such sale, depending entirely upon the methods of production desired.

In the above described method of producing the resulting strand which will be designated by the numeral 25, the narrow binding strips or 10 strings 19, 19a may be composed of contrasting material both as to texture and color to produce an ornamental effect in the finished product, and if desired, what is commonly referred to as tinsel may be employed as this binder. But, in other 15 uses, a narrow cellulose strip may be employed, or in fact, a thread or cord may be used.

One of the outstanding difficulties of the old or known methods of producing strands of the general class under consideration was the objection to the stiffness of the cellulose material or 20 "cellophane" which rendered it difficult, if not impossible, to make a neat package in using the same as a tie string or cord, or in fact, in using the strand for any other purpose. However, I 25 have found that by employing a saturated core of the type under consideration, said core will hold the saturant for a relatively long period of time, thus serving to maintain the cellulose or "cellophane" strip in a soft, pliable state at all times, 30 facilitating the use thereof.

In Fig. 6 of the drawing, I have shown a slight modification wherein a sheath or covering 26 is applied to the core 27, similar to the core 11, prior to the application of the cellulose strip 28 thereto. 35 At 29, I have indicated the outer binding strand or strands. With this construction, the intervening layer 26 may be composed of paper tissue or other fibrous material to give added thickness to the resulting core as well as to give added 40 strength thereto, especially in the use of a kraft paper. Whatever material is used, the saturant of the core will penetrate therethrough to contact with the cellulose covering 28 as well as the strips 29 if the latter are composed of cellulose 45 material.

In Fig. 5 of the drawing, I have shown another modification wherein two strips 30 and 31 of different or contrasting color or structure are wound upon a saturated core 32, preferably with their 50 adjacent edges overlapping so as to produce a two-toned effect as between the strips 30, 31, and if the thin or narrow strips or strands 33, 33a are employed, a three-toned effect may be produced. For example, the strip 30 may be green, the strip 31 red and the strands 33, 33a of a silver 55 color.

The size of the resulting cord may be governed to a large degree upon the size of the core employed which may be as fine as a thread, in 60 some cases; and in all cases, the width of the cellulose strip 17 will be made in proportion to the size of the cord, or when the spirally wound strips are employed, these may be of different widths depending upon the spiral employed and 65 the desired contour which is required in the resulting product. The strips 17, 28, 30 and 31 form a protecting shield or jacket which envelops the cord and serves to protect or preserve the saturant so as to give long life thereto, or in other 70 words, to prolong the maintenance of the soft texture or pliability of the resulting strand.

My invention is not limited to any particular arrangement or color values of the strips employed, the fundamental principle of the invention residing in the production of a strip or cord 75

of the kind under consideration, having an outer cellulose jacket with an inner core element containing a saturant for keeping the cellulose jacket soft and pliable to facilitate the use thereof.

Having fully described my invention, what I 5 claim as new and desire to secure by Letters Patent, is:

1. A strand of the class described, consisting of a core, and an outer jacket of strip cellulose material arranged upon said core containing a 10 saturant for maintaining the cellulose jacket soft and pliable.

2. A strand of the class described, consisting of a core, an outer jacket of strip cellulose material arranged upon said core containing a saturant for maintaining the cellulose jacket soft and pliable, and a narrow binding strand spirally wound upon said jacket. 15

3. A strand of the class described, consisting of a core, an outer jacket of strip cellulose material arranged upon said core containing a saturant for maintaining the cellulose jacket soft and pliable, a narrow binding strand spirally wound upon said jacket, and said jacket comprising a strip of "cellophane" folded around and 25 enveloping said core.

4. A strand of the class described consisting of a core, an outer jacket of strip cellulose material arranged upon said core containing a saturant for maintaining the cellulose jacket soft 30 and pliable, and said core comprising a cotton cord.

5. A strand of the class described consisting of a core, an outer jacket of strip cellulose material arranged upon said core containing a saturant for maintaining the cellulose jacket soft and pliable, and said core comprising a cotton cord of a color substantially common with the color of the cellulose strip employed. 35

6. A strand of the class described consisting of a core, an outer jacket of strip cellulose material arranged upon said core containing a saturant for maintaining the cellulose jacket soft and pliable, said core comprising a cotton cord of a color substantially common with the color of the cellulose strip employed, and a narrow strip of 45 contrasting material spirally wound upon said jacket to aid in securing the jacket on said core.

7. A strand of the class described comprising an elongated fibrous core treated with a saturant, 50 a cellulose strip mounted upon and extending longitudinally of said saturated core and maintained in a soft pliable state by the saturant employed in said core, and means for retaining said strip in said core.

8. A strand of the class described comprising 55 an elongated fibrous core treated with a saturant, a cellulose strip mounted upon and extending longitudinally of said saturated core and maintained in a soft pliable state by the saturant employed in said core, and means for retaining said strip upon said core.

9. A strand of the class described comprising an elongated fibrous core treated with a saturant, 60 a cellulose strip mounted upon and extending longitudinally of said saturated core and maintained in a soft pliable state by the saturant employed in said core, and said strip being spirally wound upon said core.

10. A strand of the class described comprising 65 an elongated fibrous core treated with a saturant, a cellulose jacket mounted upon and enveloping said core and maintained in a soft pliable state by contact with the saturant of the core, and said jacket being composed of a plurality of 70 strips spirally wound upon said core.

75

- 5 11. A strand of the class described comprising an elongated fibrous core treated with a saturant, a cellulose jacket mounted upon and enveloping said core and maintained in a soft pliable state by contact with the saturant of the core, said jacket being composed of a plurality of strips spirally wound upon said core, said strips being of contrasting color.
12. A strand of the class described comprising

an elongated fibrous core treated with a saturant, a cellulose jacket mounted upon and enveloping said core and maintained in a soft pliable state by contact with the saturant of the core, said jacket being composed of a plurality of strips spirally wound upon said core, said strips being of contrasting color, and one of said strips being narrower than the other strip or strips.
